UNITED STATES PATENT OFFICE

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY

MANUFACTURE OF SHOES

Application filed June 4, 1925. Serial No. 34,838.

This invention relates to the manufacture of shoes and particularly to the fastening together of shoe parts.

Tacks, nails and other forms of metallic fastenings have long been commonly used for securing together various parts, both temporarily and permanently, in the manufacture of shoes. While there have been a number of objections and disadvantages arising from the use of such metallic fastenings, these fastenings have been so easy to insert and so generally convenient that it is probably safe to say that, aside from moccasins and the various types of rubber foot-wear, shoes have never been made on any considerable scale by any of the usual present day methods without extensive use of metallic fastenings. On the other hand, the various disadvantages arising from the use of metallic fastenings are such that their elimination or even a reduction in the number of such fastenings used, without the introduction at the same time of corresponding disadvantages, is eminently desirable.

Among the more serious disadvantages arising from the use of metallic fastenings in the manufacture of shoes are the interference with the performance of subsequent operations by fastenings inserted in connection with earlier operations, the added weight of the shoe where any considerable number of metallic fastenings are used, the liability of the points of metallic fastenings to injure the stockings or the feet of the wearer, the damage done to highly finished floor by nails and slugs, particularly those inserted in heels, and the rusting of the fastenings when of iron, as most of them are.

An illustration of a serious difficulty in the manufacture of shoes arising out of the interference with the performance of a subsequent operation by previously inserted fastenings is the breakage of needles in McKay sewing machines used to stitch the outsoles to McKay shoes and the breaking of the thread in the same machines. In the sole-laying operation in the manufacture of McKay sewed shoes a number of metallic fastenings are ordinarily driven through the outsole into the insole, these fastenings be-

ing located in the channel in which the outsole attaching seam is later to be made so that they will not be visible in the completed shoe after the channel flap has been closed. There can be no assurance in the stitching of any given shoe that the needle of the stitching machine will not be broken by striking a tack or that the thread will not be cut or injured in the same manner. As a matter of fact, the number of needles broken in this way is large and the number of shoes with defective seams so produced is even larger. In this connection, it should be remembered that the characteristic McKay seam is a chain-stitch seam and that to give it the strength it should have, it must be continuous from end to end.

Similarly, in the stitching of the outsoles to McKay shoes, lasting tacks placed too near the edge of the insoles are often hit by the needle of the McKay sewing machine. This occurs particularly if the shoe uppers are cut too short or if they are not pulled up properly in the lasting operation. Under normal conditions there is from one-sixteenth to one-eighth of an inch, more or less, of leeway between the row of lasting tacks and the outsole-attaching seam in a McKay sewed shoe, but if the latter is at all careless, he is likely to get some of the lasting tacks out where they will be hit by the needle of the stitcher.

Disadvantages arising from the use of metallic fastenings in shoes are also particularly apparent from a consideration of the manner in which the heel-seat portions of shoes have been secured together. In the heel-seat portion of a shoe as heretofore made are commonly found heel-attaching nails used to attach the heel to the shoe, heel-seat nails used to secure the outsole to the insole and upper, and lasting tacks holding the upper in lasted relation to the insole. It is not uncommon for a heel-seat nail to be deflected from its course during the heel-seat nailing operation and improperly clenched by striking a lasting tack or for a heel-attaching nail to be similarly deflected and crippled by striking a heel-seat nail, thus seriously detracting from its holding power and sometimes other-

wise injuring the shoe. Again, the presence of metallic heel-seat nails in the heel-seat portions of the soles of shoes often interferes with the heel-seat fitting operation performed preparatory to the attachment of wood heels. This is particularly troublesome when the trimming is done by a machine, for if the trimming cutter strikes a nail it is likely to be nicked if nothing worse happens. The elimination of these heel-seat nails is thus particularly desirable. Moreover, the large number of nails and tacks clenched on the inner surface of the heel-seat of the insole often becomes a source of annoyance to the wearer, particularly if the heel pod becomes displaced.

The metallic slugs commonly inserted in the top lifts of leather heels and the metallic tacks and nails used to secure the top lifts to wood heels are other examples of metallic fastenings which are not entirely satisfactory. These tacks, nails and slugs perform a necessary function in securing together the parts of the heels, and, in the case of slugs, also produce an ornamental effect which is not without value as a selling point. Also, they serve to an extent as a reinforcement. On the other hand the use of such fastenings results in the consumption of an excessive amount of sand paper during the top lift scouring operation, and, when shoes having such heels are worn, results in a great deal of damage to highly-finished floors.

In view of the foregoing and other disadvantages arising out of the use of metallic fastenings, it is an object of the present invention to provide fastenings for securing together shoe parts which will have the advantages of ease of insertion and general convenience commonly associated with the use of metallic fastenings at a cost lower than that of metallic fastenings and which will at the same time obviate the difficulties and disadvantages inherent in the use of metallic fastenings in the manufacture of shoes. With this in view, the invention provides novel fastenings of felted fibrous material for use in securing shoe parts together. I have found that paper pegs such as those cut from twisted paper twine or string may be driven into shoe parts in much the same manner as metallic fastenings. Such fastenings constitute a surprisingly effective means for securing together various shoe parts. They have a holding power comparable with that of metallic fastenings, greater in some instances, and will not damage a tool such as an awl, a needle or a trimming cutter, or another fastening which strikes one of them. These paper fastenings are not hard enough to injure floors if inserted in the top lifts of heels, and, of course, are much lighter than iron or brass nails or slugs. While these fastenings can be inserted by hand, it is, from a shoe manufacturing point of view, desirable to in-

sert them by machinery and this it is entirely practicable to do.

When these felted fibre or paper fastenings are used in the lasting operation, the shoe upper is strained to shape it over the last and to position it in lasted relation to the insole, and is secured in that relation to the insole by inserting paper pegs through the upper into the insole, and heading said pegs so as to prevent the comparatively thin upper stock from pulling off over the ends of the fastenings. This may be done, for example, by using fastenings a little longer than the depth of the holes in the stock into which they are inserted so that their entering ends reach the bottoms of the holes when the fastenings have been inserted somewhat less than their whole length into the work and regulating the driver stroke so that the projecting ends of the fastenings are upset and headed upon the shoe upper. In lasting some types of shoes it may be desirable to head both ends of these felted fibre fastenings and this also may be done, the entering ends of the fastenings being driven completely through the stock and headed against a suitable clenching surface. It should be noted here that the word "lasting" is used in connection with the heading of these fastenings in a broad sense, to include also pulling over. While the heading of these felted fibre fastenings is of special utility in connection with lasting, it should be understood that it is not limited thereto but on the contrary may be utilized in other situations where there is danger of the stock pulling off over the end of the fastenings.

In order to stiffen and lend body to the material of these fastenings, the paper twine may be impregnated with sizing material such as glue. This is commonly done in the manufacture of paper twine by passing the paper strip prior to its twisting through a bath of sizing material or over a roll which passes through such a bath. In addition, the paper pegs will be improved for many purposes if the sized twine from which they are cut is given a supplemental coating of sizing material after it has been twisted and dried. This supplemental surface coating of sizing under certain conditions increases the holding power of the fastenings. If the stock into which such fastenings are driven is slightly moist, the supplemental coating may advantageously be of water-soluble glue in which case some of the glue will be dissolved and will tend to cement the fastenings into place. If the fastenings are to be driven into dry stock they may be moistened immediately before being driven with the same advantage. On the other hand, where the fastenings are used in a situation where they are depended upon permanently to secure together shoe parts and where they may come into contact with moisture, a surface coating of a more than ordinarily water re-

sistant glue or sizing may be used, for example a water-resisting casein glue, animal glue to which has been added a little formaldehyde or a dichromate, or shellac. When fastenings sized with shellac are used, it may be desirable to soften the shellac, for example if the fastenings are to be headed, and this may be done by the application of a gentle heat or a suitable solvent such as 10 alcohol.

It may be noted here that when these fastenings are inserted by a machine running at a moderately high speed the heat generated by the action of the awl of the machine in piercing the stock and by the friction as the fastenings are inserted is sufficient to warm the material perceptibly. This augments the cementing effect of the sizing, whether of glue or shellac, and accordingly 20 increases the holding power of the fastenings.

In some of its different aspects, therefore, the invention provides fastenings, such as pegs, of felted fibrous material, for example paper, preferably sized with stiffening material such as glue; a novel method of manufacturing shoes characterized by the securing together of shoe parts by the insertion of separate fastenings of such fibrous material; and shoes, as articles of manufacture, 25 having various parts secured together by such fastenings. In such shoes, for example, the upper may be secured in pulled over and lasted position relatively to the insoles by these fibre fastenings; the heel-seat portions 30 of the outsoles may be secured to the insoles and uppers by such fastenings, the fibre fastenings serving in the place of heel-seat nails; and the outsoles may be fastened to the insoles and shoe uppers in the same way, the 35 fibre fastening either co-operating with 40 stitching to hold the outsole members in place, or serving as the entire sole fastening means.

In other aspects the invention contemplates, as articles of manufacture, various of the elements entering into shoes each having 45 its parts secured together by driven fastenings, hereinafter as a matter of convenience spoken of as pegs, of felted fibrous material.

An example of such a shoe part, in connection 50 with which the invention has important advantages, is a wood heel having a leather, rubber or composition top lift secured thereto by felted fibre fastenings driven through the top lift into the wood heel. This may 55 be done without the prior attachment of the top lift to the wood heel and results in a heel the tread surface of which is entirely free from metal and which will not injure the most highly-finished floor. Moreover, the 60 life of the sandpaper used to scour top lifts attached or slugged with these fibre fastenings is markedly greater than it is if the top lifts are attached with metallic fastenings, and the cost of scouring is correspondingly decreased. Another such shoe part in

connection with which the invention has important advantages is a heel having its rand secured to its body portion by paper pegs. If one of the paper pegs is struck by a nail when the heel is attached, the nail will not 70 be deflected and no harm will be done. Still another such shoe part is a heel unit comprising a base section, for example of leather or leather-board, having a rubber section secured thereto by felted fibre pegs. These 75 pegs can be freely used for the purposes of attaching rubber heel sections preliminarily to heel bases, and the rubber section and bases can be subsequently nailed to shoes in a single operation without danger of deflection of or injury to the heel attaching nails. In fact, where special nail receiving openings are provided in rubber heel sections for the heel attaching nails, the rubber sections 80 can be preliminarily secured to the bases by 85 felted fibre pegs driven through some of the very openings through which the heel attaching nails are subsequently driven.

While the invention is herein described in connection with the securing together of 90 shoe parts, it should be understood that in various aspects the invention is not so limited but is applicable to the securing together of the parts of other objects.

With the above and other objects and features in view, the invention will now be described in connection with the accompanying drawings and pointed out in the claims. The illustrated machines, however, are not claimed herein, since they form the subject- 100 matter of my co-pending application Serial No. 222,360 filed September 27, 1927.

In the drawings,
Fig. 1 is a sectional view on an enlarged scale showing a portion of a wood heel having a leather top lift secured thereto by a paper peg;

Fig. 2 is a sectional view, also upon an enlarged scale, of two pieces of leather secured together by a paper peg headed at both ends;

Fig. 3 illustrates a shoe upper secured in pulled-over relation to a McKay insole by a number of paper pegs;

Figs. 4 and 5 are cross-sectional views on an enlarged scale of a portion of a McKay 115 and a Goodyear welt shoe having the upper secured in lasted relation to the insole by paper pegs;

Fig. 6 illustrates a stitchdown shoe having its upper secured in lasted relation to its 120 insole by paper pegs;

Fig. 7 is a view of the heel portion of a shoe partly broken away and partly in section showing certain parts thereof secured together by paper pegs;

Fig. 8 illustrates a shoe after the performance of the heel-seat fitting operation, the heel-seat portion of the outsole being secured to the insole by paper pegs;

Fig. 9 illustrates the stitching of an outsole 130

to the other parts of a McKay shoe, the outsole having been secured in place by paper pegs during the sole laying operation;

Fig. 10 illustrates the attachment of randing to a heel by paper pegs;

Fig. 11 illustrates a wood heel having a top lift secured thereto by a row of paper pegs;

Figs. 12 and 13 illustrate the attachment 10 of rubber heel sections to leather or fibre bases by paper pegs;

Fig. 14 illustrates a shoe with a half-sole attached thereto by paper pegs;

Fig. 15 is a front elevation of a head of 15 a fastening inserting machine arranged to insert paper pegs;

Figs. 16 and 17 illustrate the securing of 20 an outsole to other shoe parts, as in McKay sole laying, by paper pegs, showing also the driver and nozzle of the machine of Fig. 15 and parts co-operating therewith, on a larger scale than Fig. 15;

Fig. 18 illustrates part of a fastening inserting machine arranged to head paper fastenings as they are inserted;

Fig. 19 is a view on a larger scale than Fig. 18 of a part of the work support, the insole and the driver of the machine of Fig. 18, illustrated as fastening the upper to the 30 insole during the lasting of a stitchdown shoe;

Fig. 20 is an enlarged view of a paper peg having its entering end of a fishtail formation so as to facilitate the clenching thereof;

Fig. 21 is a cross-sectional view through 35 the nozzle and clenching cavity of the machine of Fig. 18 on a still larger scale than Fig. 19 and illustrating the heading of a paper peg; and

Fig. 22 illustrates the insertion of paper pegs by a fastening inserting machine having a separate awl and driver.

Figs. 1 and 2 illustrate, on a much enlarged scale, pegs of felted fibrous material 45 formed in accordance with the present invention and inserted in shoe parts which are thereby secured together. Fig. 1 shows a paper peg 30 of cylindrical form inserted through a leather top lift 32 into a wood heel 34, a suitable hole having been punched through the top lift 32 and into the wood heel 34 for the reception of peg 30. It may be noted that under these circumstances, when the peg is driven into comparatively 55 hard material such as the hard leather top lift 32 and the wooden heel member 34, the paper peg retains substantially its original shape. Fig. 2 shows a paper peg 36 driven through upper leather 38, into an insole 40 to hold the upper in lasted relation to the insole, the peg 36 being headed or clenched on the upper leather at 37 and on the insole at 39. This may be done by mechanism which is hereinafter described. It may be 60 noted, however, at this time, that a peg

which is to be headed or clenched is cut of a length somewhat greater than the depth to which it is to be inserted in the stock so that there will be sufficient peg material to be upset to form the head or heads. The driver 70 stroke is regulated so that the distance between the lowest position of the peg engaging end of the driver and the bottom of the hole into which the peg is driven or the abutment or anvil against which the peg is driven is less than the length of the peg. Under these conditions the peg is headed at one or both ends, as the case may be. In heading a paper peg upon upper leather or other relatively soft stock the 80 peg will be upset through a substantial portion of its length as indicated at 42 in Fig. 2. Such an expansion of the peg is highly desirable in lasting, where the upper is relatively thin, or in any place where there 85 is a strain upon the material in a direction tending to pull it off the end of the peg.

While the material from which pegs 30 and 36 are made has been spoken of as paper twine or string, it should be understood that it is not essential that this material be made of pure paper pulp. Indeed such would not ordinarily be the case. In order to give rigidity to the pegs the paper strip from which the twine is twisted during its manufacture should be sized with an appropriate glue or other stiffening material. Also, after the twisting of the sized paper strip to form the paper twine, it may advantageously be passed through a bath of 95 glue or other suitable sizing to deposit a supplementary surface coating of sizing upon the twine. This makes the pegs still stiffer and moreover may be utilized as a vehicle for cementing the pegs into the stock 100 in which they are inserted, as is more fully hereinafter explained. Moreover, other fibres than the cellulose or ligno-cellulose of which paper is ordinarily made may be incorporated in the fastening material.

With the foregoing by way of introduction the invention will now be described with reference to a number of different illustrative applications to shoemaking, following through the different operations in approximately the order in which they are performed in the manufacture of shoes.

Fig. 3 illustrates the toe portion of a last 50 and an insole 52, with a shoe upper 54 secured in pulled-over relation to the last and insole by a plurality of paper pegs 56. These fastenings 56 are driven into the insole but of course do not enter the last, the holes punched for their reception extending very nearly but not necessarily quite through 115 the insole. In order that the fastenings 56 may be headed as indicated at 57 so as more securely to hold the shoe upper in place, they are cut long enough so that the entering end of each fastening reaches the bottom of 120 125 130

the hole punched through the shoe parts as an incident to its insertion before the upper end of the fastening and the fastening engaging end of the driver reach the surface of the shoe upper, and the stroke of the driver is continued to upset and head the end of the fastening upon the shoe upper after it reaches that position.

Applications of the invention to lasting are shown in Figs. 4, 5, 6 and 7. In Fig. 4 is shown a cross-section of a portion of a last 60 with a McKay shoe lasted thereon. The shoe upper 62 and the lining 64 are secured to the insole 66 by paper pegs 68, the illustrated peg being headed upon the upper 62 in the manner shown at the upper end of peg 36 in Fig. 2 to prevent the upper from pulling off the peg. In this connection it may be remarked that the size of the head formed as described in connection with Fig. 2 may be varied by suitable variation in the length to which the peg is cut.

Fig. 5 illustrates a cross-section through a part of a last 70, a Goodyear welt insole 72 and shoe upper and lining 74 secured in lasted relation thereto by a series of paper pegs passing through the shoe upper and lining into the rib 76 of the insole. One of these paper pegs is illustrated at 78 and is headed at both ends, as hereinbefore described.

Figs. 6 and 21 illustrate stitchdown shoe 80 having the margin 82 of its upper secured in lasted relation to its insole 84 by paper pegs 86 inserted through the margin of the upper into the insole. These pegs may advantageously be headed at both ends, as illustrated in Figs. 2 and 21.

Fig. 7 illustrates the heel portion of a shoe 90 having the margin 92 of its upper secured in lasted relation to its insole 94 by a series of paper pegs 96 headed upon the upper leather.

Fig. 8 illustrates a shoe of the McKay type having its outsole 91 attached to its insole 93 by through-and-through stitching 95 and having its upper 97 held in lasted relation to its insole 93 by paper pegs 144, 147, extending through the upper into the insole and headed upon the upper.

An operation in connection with which these paper pegs are particularly useful is McKay sole laying. After the lasting of a McKay sewed shoe, and preparatory to the McKay sewing operation by which the outsole is stitched to the shoe upper and insole by through-and-through stitching, the outsole is commonly tacked to a lasted upper and insole by a number of tacks driven in the heel-seat portion of the sole and in the channel in which the McKay seam is afterwards to be sewed. These tacks are very troublesome, since there is always danger of their being struck by the needle of the McKay stitcher, in which case the needle is likely to be broken. Moreover, even when the needle does not strike a tack there is danger of the

thread being damaged and weakened by a tack against which it is pulled. The paper pegs of the present invention are well adapted to use in this McKay sole laying operation and are of such a nature that if one of them is hit by the needle of the McKay stitcher no damage is done. Moreover, they will not cut or damage a thread which is pulled against one of them.

Fig. 9 illustrates a shoe 100 having its outsole 104 secured to its upper and insole by several paper pegs 106 located in the heel-seat portion of the sole and by a number of paper pegs 108 located in the channel of the outsole and driven through the outsole and shoe upper into the insole. In Fig. 9 is also illustrated the needle 110 of a McKay stitcher with a portion 112 of the McKay seam which has been inserted thereby. Needle 110 is about to strike a fastening 114 as illustrated in dotted lines at 115. This is something which will frequently happen and by the present invention is converted from an annoying accident to an unnoticed and harmless incident.

The utility of the supplemental coating or sizing hereinbefore referred to as of assistance in cementing the paper pegs into the stock in which they are inserted should be noted in connection with the sole laying operation. When the paper pegs are inserted the stock is slightly moist or in temper so that at least a part of the surface coating of glue tends to dissolve and penetrate the leather, thus cementing the fastenings into the stock. Thus a small number of pegs spaced well apart are sufficient to hold the sole in place.

After the outsole has been attached to a shoe, whether Goodyear welt or McKay, it is usual to nail the heel-seat portion of the sole to the shoe upper and insole. The use of paper pegs for this heel-seat nailing is illustrated at 120 in Fig. 7. This figure, moreover, illustrates the entire elimination of metallic fastenings from the heel-seat portion of a shoe and in that figure not only is the margin of the shoe upper held in lasted relation to the insole by paper pegs 96 headed upon the shoe upper and the outsole secured by paper pegs 120 extending about the heel-seat and also all the way around the sole and thereby serving as the outsole attaching means, but the heel 122 is attached by paper pegs 124 and is slugged with paper pegs 126. If, during the heel-seat nailing operation, one of the paper pegs 96 which serve as lasting tacks is struck, the entering peg will not be deflected but will continue in its intended path. Similarly, if a heel-attaching peg 124 strikes one of the heel-seat nailing pegs 120 it will not be deflected. Moreover, the heel portion of a shoe thus constructed is substantially lighter than that of a shoe in which metallic fastenings are used.

Paper pegs are particularly advantageous

for securing in place the heel-seats of the soles of shoes to which wood heels are to be attached, as shown in Fig. 8. The iron nails or tacks heretofore used for this purpose often 5 interfere with the heel-seat fitting operation, the knife or other trimming tool used to remove the surplus stock from the heel-seat portion of the sole often being injured by striking a tack. The possibility of such injury is eliminated by the use of paper fastenings, as 10 shown at 130 in Fig. 8, for if one of these paper fastenings is cut, as shown at 132, during the heel-seat fitting operation, no harm is done to the trimming tool. A somewhat 15 similar condition exists in connection with the trimming of the surplus upper stock from the toe portion after the lasting of shoes having pointed toes. The fullness of the upper under these conditions is pleated or otherwise 20 bunched, being forced into this condition during the lasting operation. The metal tacks commonly used about the toes of McKay shoes interfere with the trimming off of this surplus stock. When paper pegs are used in 25 place of lasting tacks, however, as illustrated at 144 in Fig. 8, this difficulty is overcome and no harm will be done if the trimming tool used to remove the surplus stock hits one or several of the paper fastenings.

30 Figs. 10, 11, 12 and 13, as well as Fig. 7, illustrate a number of different types of heels having their parts secured together by paper pegs. Thus, in Fig. 10 a heel built up of a series of leather or leather-board lifts 150 is 35 illustrated as in the process of having a piece of randing 152 attached by a row of paper pegs 154. As illustrated, the pegs are inserted by a driver 156 operating through the nozzle 158 of a fastening-inserting machine, 40 the randing 152 being guided into attaching position by a rand guide 160. After the attachment of the randing the heel may be compressed as a unit, and the paper fastenings will compress with the material of the heel.

45 If one of these paper fastenings is struck by a heel-attaching nail the nail will continue in its intended course without deflection.

Fig. 11 illustrates a heel having a body portion 170 of wood and a top lift 172 composed of a rubber or rubber composition portion 174 and a plywood fastening retaining element 176. The paper pegs 177 extend through the top lift into the wood heel and serve both as ornamental slugs and as retaining 50 means to secure the top lift to the heel. For this purpose the paper pegs are cut no longer than the depth of the hole punched in the heel during the fastening insertion. While these fastenings are shown as round in 55 cross-section in Fig. 11, it should be understood that they may be of other shapes if desired. While a top lift having a plywood nail receiving element is well adapted for attachment to wood heels by the paper pegs of the 60 present invention, it should be noted that

leather top lifts and top lifts of rubber or rubber composition without the plywood reinforcement may be attached in the same manner with entirely satisfactory results. If desired, the paper twine from which the fastenings are cut may be colored either to match or to contrast with the color of the lift in which the fastenings are inserted.

Since rubber heels have come into extensive use their attachment to shoes as a shoe manufacturing operation (as distinguished from shoe repairing) has presented a number of difficult problems. Ordinarily the bases upon which the rubber sections are supported have been attached to the shoes prior to the attachment of the rubber sections or else the bases and rubber sections have been coated with rubber cement and after the cement has become tacky they have been put together manually so that the two might be nailed on at a single operation. The present invention provides a convenient and inexpensive method adapted for use in the attachment of rubber heels which permits the nailing of the bases and rubber sections to the shoes at a single operation without the use of cement. Thus Fig. 12 illustrates the attachment to a leather base 186 of a heel section or lift 180 provided with a series of washers 182 with the usual conical openings 184 leading thereto. This rubber section 180 is secured to the leather base 186 by a group of paper pegs 188 driven through the holes in some of the washers. As illustrated, the nozzle 190 of a fastening-inserting machine is inserted in a conical opening 184 and a fastening is driven by a driver 192 against a suitable anvil or abutment 194. When the heel thus assembled is nailed to a shoe the heel-attaching nails are driven through the washers through which the paper pegs have previously been inserted, as well as through the other washers, the paper pegs being displaced by the heel-attaching nails.

Fig. 13 illustrates a heel having a rubber lift or section 200 provided with a nail-receiving element 202 of a suitable fabric, the rubber section being secured to a base 204 by a plurality of paper pegs 206. These pegs are driven beneath the surface of the rubber section 200. When the driver is withdrawn the rubber closes together over the fastenings thus inserted, the sections thus being blind nailed together. By cutting the paper pegs a little longer than the distance between the lowermost point reached by the driver and the anvil against which the fastenings are driven the fastenings may be somewhat upset and headed in the rubber.

For convenience, the term "rubber" is used in this specification and the accompanying claims to designate a heel section or lift, but it should be understood that it is used in the sense which is customary in the heel art, namely, as designating any of the various

resilient materials or compounds suitable for use in the manufacture of cushion heels.

Fig. 14 illustrates a shoe having a half-sole 212 secured thereto by a row of paper pegs 214. A whole sole may be attached in the same manner, as described in connection with Fig. 7. If desired the sole-attaching paper pegs may be inserted in a channel as indicated in Fig. 17. These pegs may be relied upon to hold the sole member in place, whether the latter is applied in the original manufacture of the shoe or as a shoe repairing job. Similarly these paper pegs may advantageously be used to secure in place the toe of the outsole of a McKay stitched shoe, as shown in Fig. 9, in place of the nails or staples commonly used when the toe is too pointed to make it desirable to run the stitching clear around. For purposes such as these the glue with which the paper pegs are sized may advantageously be of a water-resisting nature, for example casein, glue, or any high-grade animal glue to which a little formaldehyde or dichromate has been added. While such glues may not be water-proof in the strictest sense of the term they are water resistant to a very substantial degree and the paper pegs thus treated hold adequately even when the shoe is worn under exceptionally adverse conditions.

The paper pegs herein described may be inserted by fastening-inserting machines of various types. A novel machine adapted for this purpose is illustrated in Figs. 15, 16 and 17 and will now be described. This machine is provided with a reel 230 containing a supply of fastening material in the form of a strip or string 232 from which the individual fastenings are cut. For this purpose, as shown in Figs. 16 and 17, the strip 232 passes through a passage 234 formed in a guide member 235 and is thus directed into an opening 236 formed in a slide block 238. Slide block 238 is reciprocated by suitable mechanism to shear individual fastenings from the strip 232 and to transfer the sheared fastenings into alignment with a hole 240 in the guide member 235, the hole 240 acting also as a driver guide for the driver 242 of the machine. The driver 242 is carried by a driver bar 244 (Fig. 15) provided with a lifting block 246 arranged in the path of movement of a rotating cam 248, the latter having two lifting elements 250 and 252 so that the driver bar and driver are lifted twice in each cycle of operation of the machine. A spring 254 is provided to force the driver bar and driver downwardly when the lifting block 246 escapes from the lifting member 250 or 252 of cam 248. During the first stroke of each cycle of operation of the machine the driver acts as an awl and punches a hole in the material. Accordingly, the full stroke of the driver is such as to project it beyond the nozzle 256 of the ma-

chine. During the second stroke the driver operates to insert a fastening which has been severed from the strip 232 and moved into alignment with the opening through nozzle 256 and for this purpose it is necessary that the stroke of the driver shall be shorter than its punching stroke. Accordingly, lifting block 246 is provided with an adjustable stop member 258, and a co-operating stop 260 is arranged for movement into and out of operative relation thereto. Stop 260 is carried by a lever fulcrumed at 262 to the head of the machine and provided with an arm 264 carrying a roll 266 held in operative relation to a cam 268 by a spring 270. The form of cam 268 is such that during the first stroke of the driver bar in each cycle of operation stop 260 is moved to the right, as viewed in Fig. 15, so that it is ineffective, the driver bar continuing its downward motion until a block 272 carried by the driver bar contacts with a stop 280. Just prior to the commencement of the second stroke of the driver bar 244, however, stop 260 is moved to the left beneath stop 258 so that the stroke of the driver is short, and it moves only far enough to insert the fastening in the work.

Means for operating the slide block 238 to sever fastenings from the strip and to transfer them to the driver passage 240, means for feeding the fastening strip, and means for operating cam 248 may be provided in accordance with the usual practice in connection with spring-drive fastening inserting machines of the type which sever fastenings from a wire, for example as disclosed in United States Letters Patent No. 910,147, granted January 19, 1909, on an application filed in the name of Frederick H. Perry.

Since, in accordance with the present invention, it may be desired to moisten the fastenings immediately before they are inserted, the illustrative machine is provided with a reservoir 284 from which liquid may pass through a tube 286 to a piece of felt or other suitable material 288 (Figs. 16 and 17) arranged to moisten the fastenings as they pass through the opening in the nozzle 256. The nature of the liquid used for this purpose will depend upon the nature of the surface coating of the fastening material. If the fastening material is sized with glue the fastenings may be moistened with water, while if sized with shellac, they may be moistened with alcohol.

The machine of Figs. 18 and 19 illustrates a construction adapted to facilitate heading of the paper fastenings. This machine, which may be for the most part like the machine of Fig. 15, is provided with a work support 302 mounted for vertically sliding movement in ways 304 carried by a bracket 306 secured to the column of the machine. The work support 302 includes a sliding

block 308 provided with an opening 310 of a size to receive the driver 242 of the machine. The block 308 is arranged for backward and forward movement so that the 5 opening 310 is moved forward into alignment with driver 242 when the latter is serving as a punch or awl and rearward so as to bring a clenching cavity 312 into alignment with the driver when the latter is operated to insert a fastening. As illustrated, 10 the clenching surface 312, which is formed on the upper end of a removable pin 313 clamped in a hole formed in block 308, is shaped to head a fastening having a fish-tail point and for this purpose the upper 15 surface of slide block 314 and the co-operating lower surface of guide member 315 are of an angular formation, as illustrated at 316, so as to sever pegs of the shape illustrated in Fig. 20. Pegs cut in this fashion and 20 of a length a little longer than the thickness of the work may be headed in the manner shown in Fig. 21. Appropriate means for moving block 308 back and forth between 25 punching and fastening-inserting position is illustrated in Fig. 18. Block 308 is mounted in a slideway 318, a pin 320 carried by block 308 co-operating with a slot 322 formed in the side of way 318 and limiting 30 the backward and forward movement of block 308. A spring 324 (Fig. 19) having a bearing at one end against a shoulder 326 formed in block 308 and at the other end against a pin 328 carried by way 318 tends 35 to move block 308 to its forward position with hole 310 in alignment with driver 242. A bell crank lever 330 fulcrumed at 332 to the frame of the machine has a depending arm bearing against a pin 334 carried by the 40 rear of block 308 and moves the latter rearwardly when rocked in a clockwise direction, as viewed in Fig. 18. The rearwardly extending arm of bell crank lever 330 is connected to a vertically movable rod 336 having 45 a sliding bearing 338 in the frame of the machine and carrying at its upper end a cam roll 340 located in the track of a cam 342 carried by the main drive shaft of the machine. Cam 342 is of such a formation that block 308 is permitted to move forward 50 to bring the opening 310 into alignment with driver 242 of the machine during the punching stroke of the latter, the chips punched from the work being ejected 55 through the hole 310, as shown in Fig. 19. After the hole has been punched and the driver starts upward block 308 is moved rearwardly to bring clenching cavity 312 into alignment with the driver, as illustrated 60 in Fig. 21, and when the fastening is driven it is headed as shown in that figure.

While the insertion of paper pegs has been described herein as performed by a machine having a single tool which acts both as 65 an awl and a driver, it should be understood

that they may be also inserted by a machine having a separate awl and driver. This is illustrated in Fig. 22 wherein the layers of work are shown as supported upon the end of a horn 400 operatively positioned relatively to the awl 402 of a fastening-inserting machine, the awl being operated both to perforate and feed the work as is usual in loose-nailing and slugging machines. A driver 404 operates through a driver guide 406 and a throat 408 to insert the paper pegs, the various parts being operated in the manner usual in loose-nailing and slugging machines.

Having described my invention, what I claim as new and desire to secure by Letters Patent of the United States is:—

1. A peg of felted fibrous material.
2. A paper peg.
3. A twisted paper peg.
4. A peg composed of sized paper.
5. A peg composed of twisted, sized paper.
6. A peg composed of paper impregnated with glue.
7. A paper peg impregnated with stiffening material and coated on the outside with a supplemental layer of stiffening material.
8. Fastening material comprising a string of felted fibrous material impregnated through and through with stiffening material and coated with a supplemental layer of stiffening material.
9. Fastening material comprising twisted paper string impregnated through and through with stiffening material and coated with a supplemental layer of stiffening material.
10. That improvement in methods of manufacturing shoes characterized by securing together shoe parts in desired relation by driving paper pegs into said parts.
11. That improvement in methods of manufacturing shoes characterized by severing paper pegs from a strip of paper fastening material and securing together shoe parts in desired relation by driving said paper pegs into said parts.
12. That improvement in methods of manufacturing shoes characterized by forming registering holes in shoe parts, severing paper pegs from a strip of paper fastening material, and securing together said shoe parts in desired relation by driving said paper pegs into said registering holes in the shoe parts.
13. An improved method of inserting fastenings of sized material characterized by softening the sizing at the surface of the fastenings immediately prior to the insertion of the fastenings.
14. That improvement in methods of securing together shoe parts which comprises moistening adhesive-coated pegs of felted fibrous material and inserting the moistened pegs into holes formed in the shoe parts.
15. That improvement in methods of man-

- ufacturing shoes which comprises securing shoe parts together by paper fastenings provided with a coating of glue and softening the glue on each fastening immediately before that fastening is inserted. 5
16. That improvement in methods of manufacturing shoes characterized by securing together shoe parts in desired relation, by driving paper pegs into said parts, and heading said paper pegs at least at one end. 10
17. A shoe having parts thereof secured together by pegs of felted fibrous material. 18. A shoe having parts thereof secured together by paper pegs. 15
19. A shoe having parts thereof secured together by twisted paper pegs. 20
20. A shoe having parts thereof secured together by twisted paper pegs, each headed at least at one end. 25
21. A shoe having parts thereof secured together by paper pegs impregnated with stiffening material. 22
22. A shoe having parts thereof secured together by paper pegs impregnated with water-resisting glue. 25
23. A shoe having parts thereof secured together by twisted paper pegs sized with glue. 24
24. That improvement in methods of manufacturing shoes which comprises securing the marginal portion of a shoe upper to a sole by paper pegs driven through the upper into the sole. 30
25. That improvement in methods of manufacturing shoes which comprises securing the marginal portion of a shoe upper to an insole by paper pegs driven through the upper into the insole. 35
26. That improvement in methods of manufacturing shoes which comprises shaping a shoe upper over a last and securing the upper to an insole on the last by paper pegs driven through the upper into the insole. 40
27. That improvement in methods of lasting shoes which comprises positioning an upper in lasted relation to an insole, and, while holding the upper in that relation, fastening it to the insole by inserting paper pegs through the upper and into the insole and heading the pegs on the upper. 45
28. That improvement in methods of lasting shoes which comprises subjecting an upper to lasting strain to shape it over a last and to position it in lasted relation to an insole, and, while holding the upper under lasting strain, fastening it to the insole by inserting paper pegs somewhat less than their entire length through the upper and into the insole and heading the projecting portions of said pegs. 50
29. That improvement in methods of securing together shoe parts in the desired relation which comprises driving pegs of felted fibrous material somewhat less than their entire length into said parts and heading the projecting portions of said pegs. 55
30. A shoe having its upper secured in lasted relation to a sole by paper pegs. 31. A shoe having its upper secured in lasted relation to its insole by paper pegs extending through the upper into the insole and headed upon the upper. 70
32. A shoe having its upper secured in lasted relation to its insole by paper pegs extending through the upper and the insole and headed upon both the upper and the insole. 75
33. A shoe of the type in which the outsole is secured to the insole by through-and-through stitching, having its upper secured to its insole by permanent lasting fastenings comprising a row of paper pegs extending through the upper and the insole farther from the edge of the insole than the outsole stitching. 80
34. A shoe having its upper secured to a sole by twisted paper pegs. 85
35. That improvement in methods of manufacturing shoes characterized by securing an outsole to an insole and lasted shoe upper by driving paper pegs through the outsole and the edge of the lasted upper into the insole. 90
36. That improvement in methods of manufacturing shoes which comprises positioning an outsole relatively to a lasted shoe upper and insole in the relation which it is to bear in the finished shoe, preliminarily securing the outsole to the insole by a plurality of paper pegs, and thereafter additionally securing the outsole to the insole and shoe upper. 95
37. That improvement in methods of manufacturing shoes which comprises positioning an outsole relatively to a lasted shoe upper and insole in the relation which it is to bear in the finished shoe, preliminarily securing the outsole to the insole by a row of twisted paper pegs, and thereafter stitching the outsole to the insole and shoe upper with the line of stitching substantially coinciding with the row of paper pegs. 100
38. That improvement in methods of manufacturing shoes characterized by securing a channeled outsole to a lasted shoe upper and insole by driving a plurality of paper pegs through the outsole in the channel into the upper and insole. 105
39. That improvement in methods of manufacturing shoes characterized by securing a channeled outsole to a lasted shoe upper and insole by driving a plurality of paper pegs through the outsole in the channel into the upper and insole, and thereafter additionally securing together the insole, the upper and the outsole by a line of stitching also located in the channel. 110
40. A shoe having an outsole secured to an insole by a plurality of pegs of felted fibrous material. 115
- 120
- 125
- 130

41. A shoe having an outsole secured to an insole by a plurality of paper pegs.
42. A shoe having an outsole secured to an insole by a plurality of twisted paper pegs impregnated with water-resisting sizing.
43. A shoe having a channeled outsole secured to an insole by a plurality of paper pegs located in the channel and extending through the outsole into the insole, and additionally secured by a line of stitching also located in the channel.
44. A shoe having the heel-seat portion of its outsole secured to its upper by fastenings composed of felted fibrous material.
45. A shoe having the heel-seat portion of its outsole secured to its insole and upper by a series of paper pegs.
46. A shoe having a heel secured thereto by a plurality of paper pegs.
47. That improvement in methods of assembling heels characterized by securing a rubber heel section to a heel base by driving paper pegs through the rubber heel section into the base.
48. That improvement in methods of manufacturing shoes characterized by securing together a cushioning section and a base by inserting pegs of felted fibrous material through holes in the cushioning section through which the heel-attaching nails are later to be driven.
49. That improvement in methods of manufacturing shoes characterized by securing together a rubber heel section and a base by inserting paper pegs through holes in the rubber heel section into the base and thereafter securing the heel to a shoe by inserting heel-attaching nails through said holes.
50. That improvement in methods of manufacturing shoes which comprises locating a heel base section and a cushioning section in the relative positions which they are to occupy in the finished shoe, driving a plurality of paper pegs through some of the washers of the cushioning section into the base section to secure the two sections together, locating the heel thus assembled in the position which it should occupy relatively to a shoe to which it is to be attached, and attaching the heel to the shoe by a plurality of heel-attaching nails passing through the washers of the cushioning section, including the washers through which the paper pegs have been previously inserted, and through the base section into the sole of the shoe.
51. A heel unit having a plurality of sections secured together by fastenings composed of felted fibrous material.
52. A heel unit made up of a plurality of parts secured together by fastenings of felted fiber impregnated with stiffening material.
53. A heel unit made up of a plurality of parts secured together by paper pegs.
54. A heel having a top section secured thereto by a plurality of paper pegs.
55. A heel having a top section secured thereto by a series of paper pegs impregnated with water-resisting sizing.
56. A heel comprising a rubber section, a base, and a plurality of fastenings of felted fibrous material securing the rubber section to the base.
57. A heel comprising a rubber section, a base, and a plurality of paper pegs securing the rubber section to the base.
58. A heel comprising a top lift and a wooden base secured together by fastenings of felted fibrous material extending through the top lift into the base.
59. A heel comprising a wooden base section and a top lift secured thereto by a row of paper pegs extending through the top lift into the base.
60. A heel comprising a wooden base section and a top lift secured thereto by a plurality of twisted paper pegs impregnated with water-resisting glue, inserted through the top lift into the base.
61. A heel comprising a wooden base section and a rubber top lift with a fastening-retaining element at its attaching surface, said base section and top lift being secured together by a row of fastenings of felted fibrous material extending through the top lift and its reinforcing element into the base.
62. A heel comprising a base section and a rubber tread section having a fastening-retaining element at its attaching surface, the base and the tread sections being secured together by paper pegs extending through the tread section into the base.
63. A heel comprising a wooden base section and a rubber top lift with a wooden fastening-retaining element at its attaching surface, the top lift and base section being secured together by a row of paper pegs extending through the top lift into the base.
64. A heel slugged with pegs of felted fibrous material.
65. A heel slugged with paper pegs.
66. A heel slugged with twisted paper pegs impregnated with water-resisting sizing.
67. A top lift slugged with paper pegs.
68. A heel unit having a rand secured thereto by a plurality of paper pegs.
- In testimony whereof I have signed my name to this specification.
- FRED N. LA CHAPELLE.
